RADIATOR PRESSURE CAP

Carl H. Lines, Connersville, Ind., assignor to
Stant Manufacturing Company, Connersville,
Ind.

Application August 20, 1943, Serial No. 499,375

5 Claims. (Cl. 220—44)

1

This invention relates to a closure device and particularly to a cap or cover for the filler opening of a radiator for automobiles or the like. More particularly it relates to caps of the class having pressure and vacuum relief valves for controlling the fluid pressure within the radiator.

The main object of the present invention is to provide a device of the class described in which the sealing means is arranged so as to remain non-rotative relative to the filler neck during application and removal of the closure cap when the sealing members are in sealing contact with the sealing seats on the filler neck. The primary purpose of this is to reduce rotative resistance thereby requiring less manual effort to apply the cap to the filler neck.

Another object is to provide a structure in which there is no sliding action between the sealing members and the gaskets, the life of the gaskets is thereby greatly prolonged and a perfect seal is obtained for a comparatively longer period of use.

Another object of the present invention is to provide a closure for the purposes set forth, which is of novel construction and which is particularly adapted to low cost volume production.

Another object of the present device is to provide a permanent gasket for the lower seal which is part of the closure proper and is not likely to become damaged or lost as are those in ordinary constructions.

Another object of the present invention is to provide a device for the purpose described which is of comparatively simple construction and particularly well adapted for assembly and disassembly.

With these and other objects in view, the invention consists in certain novel features of construction and combinations and arrangements of parts as will be more fully hereinafter described and pointed out in the claims.

For a better explanation of the invention, reference will be made to the accompanying drawing wherein;

Fig. 1 is a vertical sectional view taken at substantially the midpoint showing the closure in closed position on a filler neck;

Fig. 2 is a detail perspective view of the valve cage;

Fig. 3 is a section on line 3—3 of Fig. 1 showing detail construction of the bottom plate only;

Fig. 4 is an enlarged vertical sectional view of a portion of the bottom plate taken on line 4—4 of Fig. 3.

Fig. 5 is an enlarged sectional view of a por-

tion of a modified form of bottom plate showing the gasket carried by the flange thereof.

Referring now in detail to the accompanying drawing the numeral 6 designates the filler neck; on the upper end of the filler neck there is provided an annular sealing seat 7 and projecting radially and downwardly therefrom conventional spaced entrance notches, cams and stops which are partially shown at 8. The lower end of the filler neck is turned inwardly forming an annular ledge or lower sealing seat 9 which also provides a means for securing the filler neck to the upper tank 10 of a radiator. The filler neck is also provided with a vent opening 11 through the sidewall for carrying away any fluid passed by the pressure valve. The cap body 12 is provided with downwardly and inwardly extending rigid ears 13 for cooperatively engaging the entrance notches, cams and stops 8 to detachably secure the cap to the filler neck. Depending from the cap body 12 and attached rigidly and non-rotatably thereto at substantially its center is the valve cage 14. The valve cage 14 is of bell-like shape, its upper end being formed with an annular projection 15 which defines a space of a size determined by its thickness for the purpose of loosely retaining the upper sealing arrangement comprising the spring diaphragm 16 and the gaskets 17 and 17a. The lower or open end of the valve cage is flanged outwardly as at 18 to provide a circumferential shoulder 19. One or more slots 20 are provided in the lower portion of the side wall of the valve cage and extending through the flange 18. The side wall of the valve cage is thus slotted in order to impart a capacity for a certain amount of resilient radial movement to the flange 18. The effect of the slots is to separate the cage into two resilient dependent elements located on opposite sides of the axis of rotation of the cap 12. When the bottom plate 22 is associated with the valve cage, as shown in Fig. 1, the flange 18, whose axial depth is less than that of the groove or recess 23, is freely movable within said groove or recess, so that the plate is swivelly mounted on the cage. Since the two portions of the cage body, defined by the slots 20, are resiliently movable relative to each other, the effective diameter of the flange 18 may be reduced sufficiently to permit the plate 22 to be snapped into place thereon, and to permit the plate 22 subsequently to be removed therefrom for repair or replacement of any of the parts of the assembly within said cage. Additional openings 21 may be pro-

vided so as to facilitate passage of fluid as passed by the pressure valve.

The bottom plate 22 is circular in shape and in addition to the sealing seat for sealing against the lower flange 9 of the filler neck, is formed with an annular groove 23 (Fig. 4) which is of such dimensions that it freely and rotatably receives the lower flanged end 18 of the valve cage 14. The bottom plate 22 also is provided with an annular valve seat 24 to receive the pressure valve 25, and inwardly of the valve seat is perforated at 26 and provided with a vacuum valve spring centering flange 27.

The pressure valve 25 has a central port 28 which is closed by the vacuum valve 29 and its spring 30. A compression spring 31 is provided between the pressure valve 25 and the inside top of the valve cage 14. The bottom plate 22 may be attached to the valve cage in the following manner: At several points around the periphery of the groove 23 the side wall is formed inwardly into retaining lugs 32, as may be seen in Fig. 4. These lugs are preferably of cam-like shape having a substantially flat face or ledge 33 at the lower end and a cam or incline 34 blending into the sidewall at the upper portion. The ledge 33 is spaced slightly more from the bottom of the groove 23 than the thickness of the flange 18. Assembly of the bottom plate 22 to the valve cage 14 is accomplished by locating the bottom plate over the open end of the valve cage so that the flange 18 starts to enter the groove 23, pressure is then applied and the cam shape 34 acting against the flange 18 causes the valve cage to compress (which is permitted by the slot 20) sufficiently so that the flange 18 passes over the lug 32 and rests below it in the groove 23, whereupon the valve cage springs outward to its original diameter. The ledge 33 being flat has no camming effect upon the flange 18, therefore, if it becomes necessary to remove the bottom plate, the valve cage must be compressed manually to reduce the diameter until the lugs 32 will pass over the flange 18.

Instead of a plurality of separate lugs 32 the cam section may be formed as a continuous ledge.

The gasket 35 is provided between the sealing seat of the bottom plate 22 and the lower sealing flange 9 of the filler neck to guarantee a seal at this point.

When the closure is applied to the filler neck, the sealing seat of the bottom plate and the upper sealing arrangement (16, 17, 17a) are pressed into sealing engagement with the lower sealing flange 9 and the upper sealing seat 7 respectively by the action of the cams 8 and the ears 13.

During the rotation of the cap body in applying the closure, the valve cage 14 is rotated simultaneously therewith because it is rigidly and non-rotatably attached thereto, and the bottom plate 22 and the sealing parts 16 and 17 remain stationary relative to the filler neck. The same relative movements are effected during removal of the closure. This, therefore, greatly prolongs the life of the gaskets and reduces the manual effort required to manipulate the closure. Instead of the standard construction using a separate gasket 35 between the sealing flange of the bottom plate 22 and the sealing flange 9 a gasket may be moulded permanently to the flange of the bottom plate 22 as shown in Fig. 5. This moulded gasket may consist of a resilient material such as a rubber composition suitable for sealing engagement with the seat 9. It may be

desirable to use the moulded type of gasket in a closure pressure device instead of the loose type of gasket, for various reasons; for example, the moulded gasket is obviously integral with the bottom plate 22 and therefore cannot become loose or distorted by removal of the closure cap from the filler neck. Sealing effect with the seat 9 may always be assured after closure cap has been properly positioned on filler neck and further, there is a distinct advantage in the ease by which the integral moulded type of gasket can be cleaned of any foreign matter which would interfere with sealing effect. The cooling solution in certain vehicle engines such as farm tractors contains particles of grit, sand, etc., which may become embedded in the sealing surface of a resilient gasket and if not removed, will cause an undesirable loss of cooling solution.

While I have shown the preferred form of my invention it will be understood that various changes in the combination, construction and arrangement of the parts may be made by those skilled in the art without departing from the spirit of the invention as claimed.

Having thus described my invention, what I claim as new and desire to secure by Letters Patent is:

1. A valved pressure closure device of the character described including an attaching cap for removable mounting on a filler neck, a valve enclosing cage provided with a bottom plate having portions to seat against a filler neck and to seat a pressure valve and having an annular retaining recess between the said seating portions, said valve cage being cup shaped with its upper closed end rigidly secured to the cap and its lower open end flanged with a slot extending through the flange and lower portion of the side wall adjacent the flange, said flange being slightly resilient for self retention within said recess and free relative rotation between said cage and plate.

2. In a device of the character described, a filler neck closure cap, a hollow cup-shaped member, a simple rivet passing through said cap and the base of said cup-shaped member and rigidly securing the same together, the rim of said cup-shaped member having an outwardly projecting peripheral flange, said rim having a slot traversing said peripheral flange, a bottom plate having an annular groove fitting on said flange to establish a free swivel connection with said flange, said groove having an axial depth greater than that of said flange, and said plate being shaped to provide clearance with respect to the interior of the rim of said cup-shaped member throughout the perimeter of said rim, said plate having means thereon seatable non-rotatively with respect to a filler neck to close the same.

3. In a device of the character described, a filler neck closure cap, a valve cage assembly comprising a hollow cup-shaped member of resilient material, the sides of said member being divided into separate flanged sections, relatively radially movable, at its open end, a simple rivet passing through said cap and the base of said cup-shaped member and rigidly securing the same together, the flanges of said separate sections being outwardly turned at the periphery of the rim of said cup-shaped member, a bottom plate having an annular groove fitting on said flanges to establish a free swivel connection with said flanges, said groove having an axial depth greater than the axial depth of said flanges, and said plate being shaped to provide clearance with respect to the interior of the rim of said cup-shaped

member throughout the perimeter of said rim, and a spring seated pressure relief valve within the cage sealingly engageable with said plate, said plate having means thereon seatable non-rotatively with respect to the filler neck to close the same.

4. A valved pressure closure device of the character described including an attached cap for removable mounting on a filler neck, a valve enclosing cage provided with a bottom plate having a peripheral flange, a gasket of yieldable material integrally molded upon said flange and permanently secured thereto to seat against a filler neck, said plate being formed to provide an internal seat, a pressure valve mounted for reciprocation within said cage toward and away from said internal seat, said plate having an annular retaining recess between said seating portions, said cage being cup-shaped with its upper closed end rigidly secured to the cap and its lower open end flanged with a slot extending through the flange and lower portion of the side wall adjacent the flange, said flange being slightly resilient for self-retention within said recess and free relative rotation between said cage and plate.

5. In a device of the character described, a filler neck closure cap, a cup-shaped member, a simple

rivet passing through said cap and the base of said cup-shaped member and rigidly securing the same together, the rim of said cup-shaped member having an outwardly turned peripheral flange, said cup-shaped member being provided with a slot traversing said flange and dividing the same into resiliently, relatively radially movable sections, a bottom plate formed with a groove opening toward the center of said plate and adapted to receive said flange, said plate having peripherally arranged inclined surfaces facing toward the center of said plate and leading downwardly and toward said center and, at their lower ends, joining the upper edge of said groove, whereby said resilient cage sections are cammed inwardly as said flange moves toward said groove, said groove having an axial depth greater than that of said flange whereby, when said flange is received in said groove, said plate is freely swivelly mounted thereon, and said plate being shaped to provide clearance with respect to the interior of the rim of said cup-shaped member throughout the perimeter of said rim, said plate further having a peripheral flange seatable non-rotatively with respect to a filler neck to close the same.
